LOUIS M. BROWN, OF BEVERLY, MASSACHUSETTS, ASSIGNOR TO UNITED SHOE MACHINERY COMPANY, OF PATERSON, NEW JERSEY, A CORPORATION OF NEW JERSEY.

REBOUND CONTROL FOR LASTING-CARRIAGES.

1,114,338.

Specification of Letters Patent.

Patented Oct. 20, 1914.

Application filed December 31, 1910. Serial No. 600,272.

To all whom it may concern:

Be it known that I, LOUIS M. BROWN, a citizen of the United States, residing at Beverly, in the county of Essex and State of Massachusetts, have invented certain Improvements in Rebound Control for Lasting-Carriages, of which the following description, in connection with the accompanying drawings, is a specification, like reference characters on the drawings indicating like parts in the several figures.

This invention relates to lasting machines and is herein embodied in the type of bed lasters which is shown in the United States Letters Patent No. 1,018,477 granted Feb. 27, 1912, Brock. In machines of this type there is a carriage upon which the heel lasting devices are mounted and which slides upon a track formed on the frame of the machine, anti-friction rollers being employed for facilitating this movement which has for its purpose to provide clearance for the application of the shoe to the last supporting devices and then to bring the shoe and the lasting devices into operative relation. A latch is provided for securing the heel lasting carriage in its advance position. While it occupies this position a heel band is closed about the heel end of the shoe, this movement being effected from the cam shaft through yielding connections and a lever which is fulcrumed in the carriage. When this latch is released, reaction of the spring takes effect through the lever fulcrumed in the carriage to thrust the carriage backwardly in a manner well understood by those familiar with this type of commercial machine.

It will be noted that the spring referred to has the double function of actuating the heel band yieldingly, whereby said band may embrace without special adjustment, lasts of different sizes, and of actuating the heel carriage automatically to a position for allowing the removal of the shoe from the machine. It has been found in practice, particularly upon those machines employed for lasting heavy shoes, that a stiff spring is required for obtaining the proper heel band closing pressure and that this spring re-acts to move the carriage backwardly with objectionable force causing a rebound which sometimes brings the carriage forwardly

again in a manner to damage the shoe which has just been lasted.

55

It is an object of this invention to make provision for controlling the rebound of the carriage.

It is another feature of this invention to combine with the yielding buffer a brake device which will become operative during the last portion of the rearward movement of the carriage to check that movement and then will coöperate with the buffer to bring the carriage to rest after a slight forward movement.

60

The invention is embodied in a buffer rod which is yieldingly mounted in the carriage and adapted to engage a stop on the frame and a spring brake arranged to engage the buffer rod frictionally and resist its rearward movement into contact with the stop on the frame and also resist the forward movement of the buffer in the rebound of the carriage.

75

The invention will now be explained in connection with the accompanying drawings and will then be pointed out in the claims.

Figure 1 is a rear side elevation of a machine of the class described equipped with this invention. Fig. 2 is a perspective view of the brake rebound controlling devices.

80

The frame 2 of the machine has a track 4 in which the heel lasting carriage 5 is movable on rolls 6 and a latch 7 secured to the carriage is adapted to hook over an upstanding projection on the track as shown in Fig. 1 to secure the carriage in its operative position. The carriage supports a heel embracing band 10 for closing movement about the heel portion of the last. A slide is actuated through a spring 14 from a lever 15 that is fulcrumed at 16 and the lower end of which stands in the path of a rocker 20 that is pivoted to the frame at 22. The rocker is actuated from the power shaft 25 and so long as the latch 7 remains engaged with the frame the power will be transmitted through the lever 15 and the spring 14 for closing and compressing the heel band around the sides of the heel. When the latch is lifted the spring contracts and turns the lever 15 with its lower end against the rocker, thereby impelling the carriage backwardly.

85

95

100

105

The carriage is provided with eyes 30 in which is guided a plunger rod 32 that has a collar 33 between which and the rear eye 30 a spring 35 is confined. A plate 36 is attached to the rear end of the track 4 in position to be engaged by the rear end of the buffer rod 32. Also attached to the rear end of the track 4 is a curved spring 40 the free end of which is bowed forwardly and 10 downwardly to present a resilient neck 41 and a buffer engaging portion 42, the front end of the spring being upturned. In the use of the devices, the buffer rod 32 first meets the portion 42 of the spring which 15 acts substantially to retard the backward movement of the buffer and in the mean time the momentum of the rearwardly moving carriage is taken up by the spring 35. The engagement of the rod 32 with the spring 40 20 tends to carry the engaging portion 42 of the spring backwardly bending the neck 41 and the curvature or formation of the spring is such that in this bending of the neck the engaging portion 42 is pressed downwardly 25 with increasing force upon the rod 32. Any formation of the spring which will reduce this automatically increasing downward pressure upon the rod 32 as the rod engaging portion of the spring moves backwardly 30 may be substituted for the particular formation herein shown. When the backward movement of the rod 32 has been arrested by the retarding action of the spring 40 with or without the final engagement of the rod 35 with the plate 36 the spring 35 re-acts against the front eye 30 to press the heel carriage forwardly also the bent neck of the spring 40 re-acts to press forwardly 35 upon the rod 32. The re-action of these two 40 springs is or may be enough to move the heel carriage forwardly to an extent that will free the rod 32 from the spring 40 or will nearly free it so that there is little or no resistance for the operator to overcome when 45 he again draws the heel carriage forwardly into operative position. The rod 32 may have a depression 31 in that portion of its face which is engaged by the portion 42 of the spring 40. As herein shown this is 50 formed as a tapering depression by a longitudinal concavity in the face of the rod. Preferably the rear end of the rod will be higher than the main portion of the rod and will thereby form a projection by which 55 the rod will hang on to the spring 40 and prevent the heel carriage from moving forwardly far enough to free it entirely from the spring. The spring 40 may be provided

with slots 46 to permit vertical adjustment for regulating its action upon the rod 32. 60

Having explained the nature of this invention and described a preferred construction embodying the same, I claim as new and desire to secure by Letters Patent of the United States:—

1. A lasting machine having, in combination, a heel lasting carriage, a track over which the carriage is moved away from lasting position, a rod yieldingly mounted in the carriage, and a bowed spring arranged 70 for frictional engagement with the rod and constructed to be distorted by continued movement of the carriage and to re-act in the direction to effect return movement of the carriage.

2. A lasting machine having, in combination, a heel lasting carriage, a track over which the carriage is moved away from lasting position, the rod 30 yieldingly mounted by the spring 35 in the carriage, 80 and the spring 40 having the portion 42 arranged to engage the rod frictionally and the neck 41 formed to be compressed by the backward movement of the rod and to co-operate with the spring 35 in moving the 85 carriage forwardly again.

3. A lasting machine having, in combination, a heel lasting carriage, a track over which the carriage is moved away from lasting position, the rod 32 having a depressed 90 face 31 and a relatively enlarged rear end, and the spring 40 arranged to ride over the rod end and engage in the depression and then be compressed, and thereafter to hang on to the rod end to retard rebound of the 95 carriage.

4. A lasting machine having, in combination, a heel lasting carriage, a track over which the carriage is moved away from lasting position, and a spring having a straight 100 portion 40 attached to an upright face of the track and extending upwardly and then forwardly at 41 and having a portion 42 bent downwardly and forwardly away from said straight portion and arranged for its 105 lower face to be frictionally engaged by a portion of the carriage, the spring being free to yield backwardly while also acting as a drag on the carriage.

In testimony whereof I have signed my 110 name to this specification in the presence of two subscribing witnesses.

LOUIS M. BROWN.
